UNITED STATES PATENT OFFICE.

JAMES B. HAMILTON, OF HOBOKEN, NEW JERSEY, ASSIGNOR OF ONE-HALF TO JOHN C. FARR, OF HOBOKEN, NEW JERSEY.

INSULATING SPLICE-COVER.

1,354,905.

Specification of Letters Patent.

Patented Oct. 5, 1920.

Application filed October 10, 1919. Serial No. 329,663.

To all whom it may concern:

Be it known that I, JAMES B. HAMILTON, a citizen of the United States, and resident of Hoboken, in the county of Hudson and 5 State of New Jersey, have invented a new and useful Improvement in Insulating Splice-Covers, of which the following is a specification.

This invention relates to a cap or cover 10 for use in insulating splices or bared portions of electric wires, and more particularly for the insulation of the splices of wires employed in electric installation as, for instance, electric light fixtures. Such 15 an article is disclosed in my United States Patent No. 1176288, dated March 21, 1916, and the present device constitutes an improvement on the article shown in the said patent.

20 My objects are to provide an article of this kind, which will effect a thorough and satisfactory insulation when applied by any ordinary workman of this art, and which does not, therefore, necessitate the application 25 of skill or experience in order to accomplish its purpose. Another object is to provide such an article which is very cheap to produce and which may be applied and removed with great ease and rapidity, will 30 accommodate itself to various sizes and irregularities in the wires or splices, and may be repeatedly used.

35 A further object consists in providing certain improvements in the form, composition and construction of the article, whereby the above named and other objects may be effectively attained.

40 A practical embodiment of the invention is represented in the accompanying drawing, in which

Figure 1 represents a side view of the article applied to a three wire splice.

Fig. 2 represents a central section of the same.

45 Fig. 3 represents a view, partly in section and partly in elevation, showing the article removed from the splice.

In electric wiring, in various forms of installation, such as the wiring of light fixtures used in dwellings and other buildings, it has been the general practice, after the bared ends of the wires have been spliced or soldered together to wrap the exposed part with an adhesive rubber tape,

which is designed to substitute for the insulation removed from the wire for the purpose of making the splice or joint, and then to cover this tape with a friction cloth tape that is calculated to compensate for the removal of the braided cord that normally constitutes the outer part of the insulation on the wire. It frequently happens that electricians select too short a piece of the rubber tape and endeavor, by stretching it, to enable it to cover the exposed 65 part. In such cases, the stretching of the tape naturally reduces its thickness, thus lessening its capacity as an insulator. And, furthermore, this tension of the rubber tape renders it susceptible of being punctured 70 or chafed through in case rough ends remain on the wire or rough points on the solder. Again, this shortness of the tape promotes a tendency to ineffective or incomplete covering at the end of the splice. 75 Under these conditions, reliance is placed on the use of the friction cloth tape but, it of itself is not a sufficient insulator; and the result of the practice outlined above is that the splices constitute weak points in 80 the installation and become a source or great danger of fire through grounding of the conductors on the metal of the outlet and junction boxes, cabinets, metal parts of fixtures, etc. Not only do these conditions 85 give rise to danger of fire, but short circuiting is also apt to result where poorly protected splices of wires of different polarity are brought into contact with each other or engage a common metallic conductor. 90

My present device is designed to eliminate all these dangers and disadvantages while, at the same time, lessening the labor and expense of these operations.

Referring to the drawings, the cap is 95 composed of some suitable elastic insulating material, such as vulcanized or semi-vulcanized rubber, and I prefer to use a rubber compound which is known in the art as "new code" rubber. It will be seen that 100 the device consists of an elongated body portion 1, an enlarged spherical closed end 2 and a flare or skirt portion 3 at the open end. The body portion is molded with a channel 4 which channel develops into an 105 enlarged space in the end 2 and into a flare at the end 3.

The splice of the wires is denoted by 5,

and I have shown an instance in which three wires 6, 7, 8 are twisted together, as this is a common form of splice.

It will be noted that the walls of the body portion 1 are relatively thick for an article of this size so as to provide sufficient insulation to comply with the National Electrical Code, and that the wall at the spherical end 2 is somewhat thicker than the walls of the body portion.

This enlarged end 2 with its thickened wall is a feature of importance for the reason that it provides an excess of insulating material at the end of the splice, which is a very vulnerable point, and also compensates for any lessening in thickness of that part of the cap owing to stretching of the material in cases where the cap is forced onto the splice so as to fit very snugly. In ordinary practice, the cap will actually be a little thicker at the end 2 than in the body portion, even after it has been applied, as indicated in Fig. 2. The channel 4 preferably has a smooth interior, but may be of irregular internal surface for the purpose of securing more complete frictional grip on splices of small wires.

The cap is made of a convenient length to cover the ordinary splice, and the flared end 3 provides a skirt which is designed to ride up on the insulated part of the wires 6, 7, 8, when the cap is fully applied, as shown in Figs. 1 and 2, so as to insure a complete covering of the exposed part.

I also make the channel 4 somewhat less in diameter than the splice upon which the cap is intended to be placed so that the elasticity of the material of which the cap is composed will cause it to tightly grip the splice and remain firmly in position. The elasticity of the material also enables a cap of a given size to be used for splices composed of wires of several different sizes, so

that it is not necessary to manufacture a different size of cap for every different purpose. For instance, a single size of cap is adaptable for use on all sizes of splices commonly found on fixtures and at outlets of house wiring installations where No. 18, No. 16, and No. 14 wires are spliced together in any two-wire or three-wire combination, and to end-splices in switch and receptacle outlet boxes and in junction boxes.

It will be understood that various changes may be resorted to in the form, composition and construction of the article without departing from the spirit and scope of my invention and hence I do not intend to be limited to the details herein shown and described, except as they may be set forth in the claims.

What I claim is:

1. An article of the character described, consisting of a hollow cylindrical body portion composed of elastic insulating material and having an enlarged hollow spherical end.

2. An article of the character described, consisting of a body portion composed of elastic insulating material and provided with a channel therein and having thick walls, said body portion also having an enlarged closed end, with a space therein, the wall of the end being thicker than the walls of the body portion.

3. An article of the character described, consisting of a substantially cylindrical hollow body portion composed of elastic insulating material and provided with an enlarged substantially spherical closed end and an enlarged substantially frusto-conical open end.

In testimony that I claim the foregoing as my invention, I have signed my name this 6th day of October, 1919.

JAMES B. HAMILTON
